UNITED STATES PATENT OFFICE.

HEINRICH SCHNEIDER, OF WINTERTHUR, SWITZERLAND.

INTERNAL-COMBUSTION ENGINE OF THE FUEL-INJECTION TYPE.

Application filed February 5, 1924, Serial No. 690,774, and in Germany February 12, 1923.

The present invention relates to internal combustion engines with which the fuel is injected without the aid of compressed air and which are provided with a projecting 5 part or a displacer on the piston head whereby at the end of the compression stroke a whirl is produced by the projection part on the piston head entering into a constricted portion of the cylinder, an annular 10 clearance being present between the constricted portion and the displacer.

According to the present invention that annular clearance, in contradistinction to the hitherto known constructions of these 15 engines, is essentially reduced to such a degree that a proper working of the piston is just possible, and a few enlarged portions or channels are provided in this annular clearance, through which channels strong 20 compact jets of air are produced when the air is displaced towards the end of the compression stroke, the fuel jets being injected into said air jets.

With known engines of this type the 25 width of the annular clearance is not reduced to a minimum amount but it is chosen substantially larger in order to provide for a sufficiently large passage area for the displaced air. Thereby a current of air is 30 generated having an annular cross-section and a uniform strength all round, which current is not suitable for atomizing single fuel jets.

Instead of this known current or jet of 35 air in the shape of a hollow cylinder or hollow cone through which the injected fuel jets pass very easily a strong, compact jet of air is necessary which completely atomizes the fuel jet injected into it and which 40 distributes as uniformly as possible the atomized fuel throughout in the combustion space.

One or more such compact air jets are generated according to the present invention 45 by providing one or more enlargements of the passage areas between the displacer and the constricted part of the cylinder, which enlargements give the necessary shape to the air jet, the remaining annular 50 clearance being kept as narrow as possible. In this way the total quantity of the displaced air is almost completely utilized for atomizing the single fuel jets, only an insignificant quantity of air which is lost for 55 atomizing purposes passes through the annular clearance wherein it is intensely

throttled. The enlargements in the passage area cause a much smaller throttling of the effective air jet than it is the case with the hitherto annular passage areas of uniform width and the heat losses at the walls 60 are also essentially reduced.

The number of the enlargements and the shape and direction imparted thereby to the fuel jets can be so chosen that with any size 65 of an internal combustion engine a complete atomizing and combustion of the fuel is attained.

By means of the compact air jets the fuel 70 may be so distributed and burnt that scarcely any traces of the fuel get into contact with the walls of the combustion space or of the displacer so that an excessive heating up and destruction of these walls, which is caused by the fuel thrown against and 75 adhering to said walls, are prevented.

Furthermore the reduction of the width of the annular clearance in combination with the arrangement of the enlargements 80 of the passage area presents the advantage that the designer has much more liberty to choose the diameter of the displacer relatively to the diameter of the cylinder as the air jets can be suitably directed and are no longer dependent on the cylinder or cone 85 shape. The present invention is of particular importance with two stroke cycle engines having an inlet valve for the scavenging air arranged in the combustion chamber as the known arrangements and dimensions 90 of the displacer cause the scavenging air on its way from the combustion space to the cylinder to be too much throttled.

Various constructional examples of the 95 subject matter of the present invention are illustrated on the accompanying drawings, in which:

Fig. 1 shows in a diagrammatic manner a vertical section through the cylinder head of an internal combustion engine with the piston in its upper extreme position,

Fig. 2 is a horizontal section along line II-II of Fig. 1,

Fig. 3 is a vertical section through the upper part of a cylinder having a centrally arranged fuel nozzle and showing the means for operating the inlet valve for the scavenging air.

Fig. 4 is a horizontal section along line V-V of Fig. 4.

Figs. 5 and 6 show in a vertical section 110 and in a horizontal section along line VII-

VII of Fig. 5 respectively a modified example having three laterally arranged fuel nozzles, and Figs. 6 and 7 show in a vertical section and in a horizontal section 5 along line IX-IX of Fig. 7, the respective parts of a four-stroke cycle engine.

Referring now to the diagrammatic illustration in Figs. 1 and 2, 1 is the engine cylinder having a constricted portion 2 into 10 which the displacer 3^a of the piston 3 enters. 5 denotes the narrow angular clearance between the displacer 3^a and the constricted portion 2 and 4 are the enlarged passage areas or channels provided in the 15 displacer 3^a. The cross-sectional area of these channels is of the same dimension as the cross-sectional area of the annular clearance with known engines. The enlarged passage areas may also be obtained by providing grooves or channels in the wall of the constricted portion as indicated in chain-dotted lines at 4^a.

In the constructional example illustrated in Figs. 3 and 4, 1 denotes again the cylinder 25 having a lining 15 and an outer shell 16 which enclose a cooling water space 17 between them, and 2 is the constricted portion or combustion space of the cylinder and arranged in the cylinder head 18. The piston 30 3 is provided with the displacer 3^a entering into the combustion space 2, on the displacer three channels or grooves 4 equally spaced around the circumference are provided for the formation of the air jets when 35 the displacer enters into the combustion space towards the end of the compression stroke. A fuel nozzle 8 is centrally arranged and provided with apertures so that a jet 9 of fuel is injected into each of the 40 three air jets 10. 11 denotes a cylindrical inlet valve for the scavenging air, the latter being supplied to the cylinder from the annular chamber 12 through the ports 13 controlled by the valve 11, the latter is actuated by means of a stirrup 14, bell crank 45 lever 19 provided with rollers 20 and 21, cooperating with cams 22 and 23 arranged on the known regulating shaft 24. 25 denotes the exhaust ports arranged in the 50 lower part of the cylinder and uncovered towards the end of the expansion stroke.

The constructional example illustrated in Figs. 5 and 6 differs from that shown in Figs. 3 and 4 inasmuch as instead of one centrally arranged fuel nozzle delivering 55 three jets of fuel three laterally arranged fuel nozzles 8¹, 8², 8³ are provided each delivering one jet of fuel injected into the respective air jet. The injected fuel is well atomized and uniformly distributed in the 60 combustion space so that a complete combustion is ensured.

The constructional example illustrated in Figs. 7 and 8 shows the part arranged according to the present invention in a four-stroke cycle engine. The displacer 3^a of the piston 3 is provided with two flattened portions 4 arranged diametrically opposite each other and the annular clearance 5 between displacer 3^a and the constricted portion 2 connecting the cylinder 1 with the combustion space 26 is narrowed to a minimum amount. Into the combustion space 26 a centrally arranged nozzle 8 injects two jets of fuel 9 into said two air jets. The plane 75 in which the centre lines of the portions 4 are situated stands at right angles to the plane through the axes of the controlling valves 27, 28.

I claim:

In an internal combustion engine of the fuel injection type in combination, a cylinder having a cylindrical constricted portion, a piston co-operating with said cylinder, a cylindrical projecting portion 80 on the piston head having a diameter that is slightly smaller than the interior diameter of the constricted portion and having a plurality of grooves in its exterior to provide a plurality of enlarged passage areas for the 85 air displaced towards the end of the compression stroke whereby narrow compact jets of air are injected into the combustion chamber, and a centrally arranged fuel nozzle having a plurality of apertures 90 adapted to inject at least one jet of fuel into every air jet produced the volume of each air jet being sufficient to completely atomize each fuel jet.

In testimony whereof I affix my signature.

HEINRICH SCHNEIDER.
